UNITED STATES PATENT OFFICE.

LLOYD BROWN, OF DES MOINES, IOWA.

THERAPEUTIC LAMP.

Application filed August 18, 1927. Serial No. 213,787

The object of my invention is to provide a therapeutic lamp of simple, durable and inexpensive construction.

More particularly it is my object to provide such a lamp in a portable construction adapted to be carried and handled in one hand and provided with adjustable carbon holding means whereby a pair of carbons can be held in position with their axes at an acute angle to each other, said device having means whereby the holders may be simultaneously adjusted by the hand that holds the support for varying the angle and the distance apart of the carbon holders and the carbons carried thereby.

With my lamp I use carbons of a special composition for securing the desired light rays, arc etc., but the composition of these carbons forms no part of my present invention.

With these and other objects in view, my invention consists in the construction, arrangement and combination of the various parts of my device, whereby the objects contemplated are attained, as hereinafter more fully set forth, pointed out in my claims, and illustrated in the accompanying drawings in which:

Figure 1 is a front elevation of a therapeutic lamp embodying my invention.

Figure 2 is a vertical sectional detail view taken on the line 2—2 of Figure 1.

Figure 3 is a vertical sectional view taken on the line 3—3 of Figure 2.

Figure 4 is a perspective view of one of the operating parts.

Figure 5 is a detail sectional view taken on the line 5—5 of Figure 3 illustrating the end of one of the carbon holders and the manner of mounting the carbon therein.

Figure 6 is a detail sectional view taken on the line 6—6 of Figure 3 illustrating the joint between one of the carbon holders and its supporting post.

In the accompanying drawings I have used the reference numeral 10 to indicate the support forming a part of my lamp and serving as a protective shield. The support 10 is in the form of a concavo-convex sheet of aluminum or any suitable material preferably having the shape of approximately one-fourth of a hollow sphere.

For convenience I shall refer to the concave face of the support 10 as its front face. Secured to the back face of the support 10

slightly below the middle thereof is a suitable handle 12. The space substantially above the handle near the upper part of the support 10 holds a sight glass 14 which is mounted in a hole in the support. This sight glass is preferably colored to permit convenient observation of the arc formed with my lamp.

Suitably mounted about mid-way of the top and bottom of the lamp and spaced on opposite sides from the middle thereof are two posts 16. For mounting the posts I cut in the support 10 suitable holes and form offset rabbets 18 around these holes. Disks 20 of fiber or other suitable insulating material are set in the rabbets 18 and cemented or otherwise securely fixed therein. Each post 16 has near its foot a flange or base 22 from which there extends in the line of the main body of the post a short foot 24 which is extended through a suitable hole in one of the disks 20. The foot 24 is threaded to receive the lock nut 26.

Conducting wires 28 and 30 may be connected with the posts 16 by additional nuts 32. The posts are thus inclined inwardly and horizontally toward each other, assuming the lamp to be in upright position, as clearly illustrated in Figures 1 and 3. The forward end of each post 16 is bifurcated to provide the spaced arms 34. Pivoted between each pair of arms 34 is a rear end of a carbon holder 36 which is connected to the arms 34 by means of a pivot pin 38. The forward ends of the carbon holder 36 are tubular having the sockets 39 to receive the carbons 40 which are adjustably locked in place by means of set screws 42 mounted in the wall of the socket portions 39 of the holders 36. A threaded screw bolt 44 projects through the support 10 preferably just above its middle point and has a screw threaded connection with the support 10. At its rear end the screw 44 has a knurled head 47. The forward portion of the screw 44 is tubular and receives the rear end of a connecting rod or link 46. The link 46 has formed in it an annular groove 48.

A set screw 50 projects through the wall of the screw 44 into the groove 48 for holding the link 46 against longitudinal movement with relation to the screw 44, while permitting the screw 44 to rotate without affecting rotation of the link 46. The link 46 has an offset portion 49 which has the spaced arms

52 which receive between them an equalizer block 54. The equalizer block 54 has a hole 56 to receive a pin 58 by which the block is pivoted to the arms 52. The equalizer block 5 54 has in its forward portion aligned slots 60 extending inwardly toward each other from the ends of the block. Projecting toward the equalizer block 54 from the respective carbon holders 36 are arms 62 which 10 are bifurcated at their free ends and are connected by pins 64 received in their respective slots 60.

In the actual use of my improved lamp the carbons 40 are installed in the holders 36. 15 The wires 28 and 30 are connected in a circuit and when a switch in the circuit is closed, the user of the lamp adjusts the screw 44 for bringing the carbons together for starting an arc and then spreads them 20 slightly. It will be observed that by adjusting the screw 44 in the support 10, the carbons can be simultaneously adjusted toward or away from each other and that their angular relation to each other can at the 25 same time be varied.

I find that in the use of a lamp of this kind it is desirable that the carbons for forming the arc should be inclined toward each other at an acute angle for directing the 30 electrons and invisible rays forwardly in a line extending from that bisecting the angle between the carbons.

It will be noted that the handle 12 can be grasped with one hand and that the thumb 35 of the same hand can be used for manipulating the screw 34.

It will be understood that I do not desire to be limited to any particular material in making my lamp and it is my purpose to 40 cover by my claims any changes in the construction and arrangement of parts which may be really included within the scope of my invention.

I claim as my invention:
45 1. In a lamp of the class described, a support, adapted to serve also as a protective shield, a handle thereon, a pair of carbon holders mounted on the opposite side of said support for adjustably holding carbons 50 at an acute angle to each other and means

actuatable from a position adjacent to the handle and on the handle side of the support and shield for adjusting said holders toward or from each other.

2. In a lamp of the class described, a 55 support adapted to serve also as a protective shield, a handle on one side thereof, a pair of carbon holders mounted on the opposite side of said support for adjustably holding carbons at an acute angle to each other and 60 means on the opposite side of the support from holders actuatable for adjusting said holders toward or from each other.

3. In a portable arc lamp, a support 65 adapted to serve as a shield, carbon holders on one side of the support adjustable for varying the angle of the carbons held and their spacing from each other, and means for effecting such adjustment including a member projecting through the support 70 whereby the carbon holders may be adjusted from behind the support.

4. In a portable arc lamp, a support 75 adapted to serve as a shield, carbon holders on one side of the support adjustable for varying the angle of the carbons held and their spacing from each other, and means for effecting such adjustment including a member projecting through the support and a handle on the other side of the support adjacent to the projecting part of said means whereby said means may be actuated by the thumb of a hand grasping the handle on the opposite side of the support from the carbon 80 holders.

5. In a portable arc lamp, a support 85 adapted to serve as a shield, posts projecting from one side of the support, carbon holders pivoted thereto for holding carbons at an acute angle to each other, a longitudinally 90 adjustable member extended through said support, means for operatively connecting said member with said holders, whereby the lengthwise adjustment of the member affects simultaneous pivotal movement of the holders for moving the ends of the carbons toward or from each other.

Des Moines, Iowa, August 4, 1927.

LLOYD BROWN.
